UNITED STATES PATENT OFFICE.

JOHN E. DE NOON, OF SPOKANE, WASHINGTON.

CLÓTHES-LIFTER.

1,134,825.

Specification of Letters Patent.

Patented Apr. 6, 1915.

Application filed November 23, 1914. Serial No. 873,544.

To all whom it may concern:

Be it known that I, JOHN E. DE NOON, a citizen of the United States, residing at Spokane, in the county of Spokane and State of Washington, have invented certain new and useful Improvements in Clothes-Lifters; and I do hereby declare the following to be a full, clear, and exact description of the invention, such as will enable others skilled in the art to which it appertains to make and use the same.

This invention relates to clothes lifters, designed for the purpose of lifting clothes from hot suds or water in wash boilers, and one of the principal objects of the invention is to provide a clothes lifter having two prongs wound on their outer ends to engage the clothes by getting certain portions of the fabric between the two prongs and twisting the clothes lifter until the clothes are thoroughly engaged before they are lifted from the boiler.

A great many persons have been scalded by hot water from a boiler owing to the fact the clothes were insecurely connected to the clothes lifter and would drop back into the boiler and splash water into the face of the user of the clothes lifter.

It is one of the principal objects of this invention to provide a clothes lifter in which such accidents would not be liable.

The foregoing and other objects may be attained by means of the construction illustrated in the accompanying drawing, in which—

Figure 1 is a sectional view through the end portion of the clothes lifter made in accordance with this invention, Fig. 2 is a detail view showing the manner of connecting the lifter members to the end of the stick, and Fig. 3 is a perspective view of the two prongs or fingers made of wire and bent into form.

Referring to the drawing, the numeral 1 designates the stick or handle of the device and this handle is provided with a recess 2 at the end thereof, and said recess is spanned by a cross piece or support 3; while the sides of the stick 1 are provided with grooves 4 for the ends of the wire forming the prongs or fingers. The cross member 3 is provided with a sharp edge 5, and the wire from which the prongs or fingers are formed is provided with a nick or notch 6 in the

center thereof. The strand of wire is passed through between the support 3 and the solid portion 7 on the stick and the notch 6 is engaged with the upper edge 5 of the supporting member 3. The two members 8 of the wire are then bent downward around the supporting member 3 and said strand is then bent around to form the outwardly projecting fingers or prongs 9 and from this point the wires are bent backwardly parallel with the members 8, and the terminal ends 10 of the wire strand are seated in the grooves 4 at the sides of the handle. A ferrule 11 is then placed on the end of the handle to hold the prongs or fingers 9 in position to engage the clothes. It will be noted that the prongs 9 slightly diverge at their outer ends.

The device may be used as follows: The fingers 9 are inserted in the hot boiler and the clothes are engaged between the same and upon twisting the lifter, the fabric is wound about the two fingers until the clothes can be lifted without danger from the hot boiler into the wash-tub.

Various changes may be made in the details of construction without departing from the spirit and scope of the invention as defined in the claims.

What is claimed is:—

1. A clothes lifter comprising a stick having a recess in the end thereof, a supporting member, and oppositely disposed grooves, a wire lifter provided with a central bend engaging said support, outwardly diverging fingers, and the terminal ends of said strand engaging the side grooves of the handle, and a ferrule for holding the wire in place.

2. A clothes lifter comprising a stick or handle having a recess at the end thereof and grooves on opposite sides of said handle, a wire lifter connected to said handle and bent around said support, said lifter having divergent fingers having curved ends, and the terminals of the wire strand forming a continuance to be seated in said grooves, and a ferrule for holding the parts in place.

In testimony whereof I affix my signature in presence of two witnesses.

JOHN E. DE NOON.
